UNITED STATES PATENT OFFICE

JASPER N. DAVIS, OF DENVER, COLORADO, ASSIGNOR TO BATTERY SERVICE STATIONS,
INC., OF DENVER, COLORADO

CONTINUOUS-CASTING MACHINE

Application filed January 21, 1928. Serial No. 248,337.

This invention relates to a machine for forming a continuous casting and is more particularly adaptable to the forming of storage battery grids in a continuous series.

5 The principal object of the invention is to provide a machine of this character which will operate efficiently to automatically form a continuous series of castings directly from a supply of molten metal.

10 Another object of the invention is to provide means for automatically clamping two halves of a mold together to form the casting and to automatically withdraw the two halves from the completed casting after it has been

15 formed.

Still another object is to provide a machine which will form castings from individual molds and fuse the casting of one mold into another so as to form a continuous series of

20 castings.

A further object resides in the means employed for heating the molds before filling and cooling the molds after filling.

25 Other objects and advantages reside in the detail construction of the invention, which is designed for simplicity, economy, and efficiency. These will become more apparent from the following description.

30 In the following detailed description of the invention reference is had to the accompanying drawing which forms a part hereof. Like numerals refer to like parts in all views of the drawing and throughout the description.

35 On the drawings:—

Fig. 1 is a side elevation of my improved casting machine, with the side supporting structure cut away on the line 1—1, Fig. 2.

40 Fig. 2 is a horizontal section taken on the line 2—2, Fig. 1.

Fig. 3 is a detail section through one of the molds, taken on the line 3—3, Fig. 1.

45 Fig. 4 is a fragmentary rear view of one of the molds illustrating details of the chain construction.

Fig. 5 is a vertical center section through the machine, taken on the line 5—5, Fig. 1.

Fig. 6 is a detail view of the lead valve controls, taken on the line 6—6, Fig. 5.

50 Fig. 7 is a detail view of the casting which

is formed when the machine is being used for the manufacture of storage battery plate grids.

The machine comprises two traveling series of molds 10 and 11, respectively. When the 55 face of one of the molds 10 is brought against the face of one of the molds 11 a complete mold for the article being manufactured is formed. The machine is adaptable to the casting of a great variety of articles and is 60 not limited to any particular use. It will be herein described as applied to the forming of storage battery grids.

The molds 10 and 11 are secured together in their series by means of links 12 placed at 65 each end of each mold upon pivot pins 13. The pivot pins 13 are extended to form studs for the support of sprocket rollers 14. Each series of molds is supported on upper shaft 15 which carries two sprocket wheels 16 that 70 support the mold series by contacting with the sprocket rollers 14 of the chain.

At the bottom of the machine each series of molds passes around a pair of sprocket wheels 17 which contact with the sprocket 75 rollers 13 and are carried on shafts 18.

The two series of molds 10 and 11 are caused to travel simultaneously and at the same speed by rotating the shafts 15 so that they will move downwardly at their adjacent 80 sides. Thus the sprockets 16 will serve as drive sprockets and the sprockets 17 simply as idlers. The face of each of the molds carries a negative imprint 19 of one half of the completed casting.

Above the molds and midway between the two series is a lead pot 20, covered by a lid 21, in which, lead or other material of which the castings are to be formed is kept in a molten condition by means of burners 22. A 85 lead discharge passage 23 extends laterally, entirely across the pot 20 and downwardly between the two series of molds. To prevent the material from congealing in the discharge passage 23, additional burners 24 are provided for heating the passage.

The flow of the metal through the passage 23 is controlled by means of simultaneously operating but alternately opening valves which are placed one above the other in the 100

passage 23. The upper valve is designated by the numeral 25 and the lower valve by the numeral 26. The two series of molds pass downwardly on each side of the passage 23 with their faces 19 in close proximity thereto. The passage radiates heat, from the molten metal it contains, and acts to heat the mold faces as they pass.

As each pair of molds 10 and 11 reach the lower extremity of the passage 23 their faces are forced together, to form a complete closed mold, by means of cams 27 and 28 which are carried on suitable cam shafts 29 and 30, respectively. The cam shafts 29 and 30 are driven by means of sprocket chains 31 from sprockets 32 on the drive shafts 32. The ratio of the drive is such that the cam shafts will revolve once for each as the mold series travels the length of a mold. After being forced together by means of the cams 27 and 28 the molds are maintained together by means of guides 33 which engage the chain rollers 14 at each extremity of each mold.

In operation the lead pot 20 is filled with metal which is melted by the heat from the burners 22 and 24. The lead flows down the passage 23 to the closed lower valve 25. The drive sprockets 16 are now put in motion causing the two series of molds to move downwardly at the center of the machine. The cams clamp a pair of the molds together below the passage 23, the lower valve 26 opens and the upper valve 25 closes.

This allows the amount of metal which has been contained between the two valves and which has been previously determined to be sufficient to fill the mold, to flow into the space between the two clamped together molds. The filled molds now move downwardly into engagement with the guides 23 while the lower valve 26 closes and the upper valve 25 opens to prepare a new measured charge of metal.

As the filled molds move downwardly they are cooled by means of an air blast from air pipes 34, which are provided with nozzles to direct the blast directly against the backs of the molds as they pass.

When the molds reach the lower extremities of the guides 33 they are pulled apart by the spaced apart positioning of the idler sprocket wheels 17 so as to release the casting which has by this time solidified. The mold faces are so arranged that each new casting is melted into the previously formed casting to form a continuous series of castings as shown at 35, Figs. 1 and 7. In the manufacture of storage battery plates this continuous casting may be cut apart at the points indicated by the broken line in Fig. 7 to form individual plates.

The metal is prevented from flowing from the sides of the pressed together molds by means of stop strips 36 between which the molds slide.

It is desired to call attention to the fact that since the upper sprocket wheels 16 act as drivers and the lower sprocket wheels 17 as idlers, the molds on the downwardly moving sides of the series will be forced tightly together since the chains at this point are being forced downwardly from the top. This positioning of the moulds is also assisted by gravity since it is their natural tendency to rest one upon the other. This prevents the molten metal from flowing outwardly between the individual moulds.

Should the radiated heat from the passage 23 be insufficient to heat the adjacent moulds a series of gas burners 37 or the like may be placed between the upper pairs of sprocket wheels so as to direct a flame against the rear faces of the moulds. These burners are carried on bent gas pipes 38 and air pipes 39.

The upper and lower valves 25 and 26 are caused to operate simultaneously by means of levers 40 and 41, respectively, which are carried on extensions of the valve shafts. These levers are operated from a connecting rod 42 which is actuated by a cam 43 on a cam shaft 44. The cam shaft 44 is driven in any desired manner such as by a chain 45 from one of the driving shafts 15.

The action of the valve mechanism is as follows: When one of the moulds has been clamped into position below the passage 23, the cam 43 will allow the connecting rod 42 to be forced downwardly by means of a spring 46 thus opening the lower valve 26 and closing the upper valve 25. As the filled mould moves away from the passage 23 the cam 43 will raise the connecting rod 42 so as to close the lower valve 26 and open the upper valve 25 for a fresh charge.

The entire machine may be driven from any suitable source of power through a belt 47 and belt pulley 48 or in any other desired manner. If necessary a brake or other drag may be applied to the lower sprocket wheels so as to force the mould faces together as they descend.

It is desired to call attention to the fact that the moulds 10 and 11 have their extremities machined to true plane surfaces at right angles to the face of the moulds so that when they are together they will fit tightly together and prevent the melted metal from escaping between the moulds. This is important for if the ends of the moulds are at an angle to each other, it will be impossible to fill the space between the moulding faces. The top strips 36 are pressed tightly against the sides of the moulds and may be held in engagement therewith by means of springs (not shown), if desired, to prevent escape of the metal and to form a completely closed mould.

To allow the moulds to be pressed together and accommodate for wear on the contacting

faces of the moulds, the pivot holes in the links 12 may be slightly elongated so that the moulds can be moved toward each other until the extremities contact.

5 Should it be found that moulds cool too rapidly so that the incoming lead does not fuse with that previously moulded, the gas pipe 38 may be continued further downwardly so that additional burners 37 may be provided. In this case, the air pipes 34 would be similarly lowered so as not to chill the moulds too quickly.

10 While I have herein illustrated and described in some detail forms of my invention, it is understood that the invention is not to be regarded limited to the precise construction described, except in so far as such limitations are included with the terms of the accompanying claims, in which it is my intention to claim all novelty inherent in my invention as broadly as is permissible in view of the prior art.

15 Having thus described the invention, what I claim and desire secured by Letters Patent is:—

20 1. A continuous casting machine comprising two traveling series of independent moulds; means for forcing a mould of one series into contact with a mould of the other series; means for supplying molten metal to the contacting moulds, said means for forcing comprising cams adapted to contact with said moulds and force them toward each other.

25 2. A continuous casting machine comprising two traveling series of independent moulds; means for forcing a mould of one series into contact with a mould of the other series, means for supplying molten metal to the contacting moulds; means for maintaining said moulds in contact until said metal congeals and side plates adapted to engage the sides of said moulds and prevent said metal from escaping, said moulds being arranged to slide along said side plates.

30 3. A continuous casting machine comprising two series of co-acting, vertically traveling moulds, the moulds in each series being independent of each other; pivoted links connecting the adjacent moulds in each series; sprocket wheels adapted to support each series of moulds; a molten metal passage extending downwardly between said two co-acting series and driven means for forcing the co-acting moulds horizontally together as they reach the lower extremity of said passage.

35 4. A continuous casting machine comprising two series of co-acting traveling moulds, the moulds in each series being independent of each other; pivoted links connecting the adjacent moulds in each series; sprocket wheels adapted to support each series of moulds; a molten metal container arranged

tending downwardly between said two co-acting series; means for forcing the co-acting moulds together as they reach the lower extremity of said passage and valves in said passage arranged to discharge a predetermined amount of molten metal between said pressed together moulds, said valves being synchronized to complete a cycle of operation as each mold passes said extremity.

5. A continuous casting machine comprising two series of co-acting traveling moulds, the moulds in each series being independent of each other; pivoted links connecting the adjacent moulds in each series; sprocket wheels adapted to support each series of moulds; a molten metal passage extending downwardly between said two co-acting series and means for forcing the co-acting moulds together as they reach the lower extremity of said passage, said means comprising positively driven cams adapted to contact with said moulds as they reach the lower extremity of said passage, said cams being so contoured as to force said co-acting moulds toward each other.

6. A continuous casting machine comprising two series of co-acting, vertically traveling moulds, the moulds in each series being independent of each other; pivoted links connecting the adjacent moulds in each series; sprocket wheels adapted to support each series of moulds; a molten metal container arranged above said series; a molten metal passage extending downwardly between said two co-acting series; valves in said passage arranged to discharge a predetermined amount of molten metal between said pressed together moulds, said valves being operated from the rotation of said sprocket wheels so that they will operate in synchronism with the travel of said moulds.

7. Means for supplying a predetermined amount of molten metal to a series of traveling moulds comprising a metal passage; a first valve adapted to control said passage and a second valve arranged to open only when said first valve is closed, both of said valves being operatively connected with said series of traveling moulds so as to operate synchronously therewith.

8. Means for supplying a predetermined amount of molten metal to a series of traveling moulds comprising a metal passage; a first valve adapted to control said passage; a second valve adapted to control said passage, said first valve arranged to open only when second valve is closed, said second valve arranged to open only when said first valve is closed and means for operating said valves comprising levers carried on extensions of said valves; a connecting rod extending between said levers and a cam adapted to move said connecting rod so as to operate said valves simultaneously, said cam being actuated by the movement of said traveling

moulds so as to actuate said moulds synchronously therewith.

9. A continuous casting machine comprising: two traveling series of independent moulds; means for forcing a mould of one series into contact with a mould of the other series, said means comprising a cam for each of said latter moulds arranged to act simultaneously upon them to force them toward each other; and means for supplying molten metal to the contacting moulds, said cams arranged to make a complete revolution during the passage of each mould.

10. A continuous casting machine comprising: two vertically traveling series of co-acting moulds each series comprising an endless linked chain; a pair of sprocket wheels for each chain positioned in vertical alignment, the two pairs being positioned apart a distance that would normally maintain the two series of co-acting moulds spaced apart; a molten metal feed passage extending downwardly and terminating between said spaced apart series; and means for forcing each pair of co-acting moulds horizontally into contact immediately below the terminus of said feed passage as they travel, said means comprising synchronously driven members adapted to act against said pair of moulds as the terminus of said feed passage is reached.

11. A continuous casting machine comprising: two vertically traveling series of co-acting moulds each series comprising an endless linked chain; a pair of sprocket wheels for each chain positioned in vertical alignment, the two pairs being positioned apart a distance that would normally maintain the two series of co-acting moulds spaced apart; a molten metal feed passage extending downwardly and terminating between said spaced apart series; and means for forcing each pair of co-acting moulds horizontally into contact immediately below the terminus of said feed passage as they travel, said means comprising synchronously driven members adapted to act against said pair of moulds as the terminus of said feed passage is reached, said driven members comprising cams adapted to contact with the rear faces of said pair of moulds when they reach the desired position.

12. In a continuous casting machine having guide tracks for maintaining two traveling series of co-acting moulds in contact; means for aligning said series with said tracks comprising synchronously operating, positively driven members arranged to move said moulds out of their line of travel and into alignment with said tracks.

In testimony whereof, I affix my signature.

60 JASPER N. DAVIS.
